UNITED STATES PATENT OFFICE.

ERNEST V. OWEN, OF CHICAGO, ILLINOIS, ASSIGNOR TO THE HOOVER COMPANY, OF CHICAGO, ILLINOIS, A CORPORATION OF ILLINOIS.

METHOD OF SEPARATING HYDROCARBON FROM ALUMINUM CHLORIDE.

Application filed January 21, 1922. Serial No. 530,991.

To all whom it may concern:

Be it known that I, ERNEST V. OWEN, a citizen of the United States, residing at Chicago, in the county of Cook and State of Illinois, have invented certain new and useful Improvements in Methods of Separating Hydrocarbon from Aluminum Chloride, of which the following is a specification.

This invention relates to a method of separating hydrocarbon from aluminum chloride, and particularly for treating aluminum chloride hydrocarbon in which the hydrocarbon has become heavy and dense, and effecting the separation in a manner that will 10 permit the aluminum chloride to be recovered in such a form that it can be used as a catalyst to treat hydrocarbon oils.

The invention proceeds upon the principle of delivering the aluminum chloride 20 hydrocarbon, preferably in subdivided form, into a bath of molten material which is maintained at a temperature in excess of the volatilizing temperature of one or some of the ingredients to be recovered, and which 25 differs sufficiently in specific gravity from the other of said ingredients to permit separation of the latter from the bath by gravity.

The invention further contemplates a preferred method of absorbing the volatiles from 30 the separating chamber and converting them into a valuable product, for instance, fresh aluminum chloride hydrocarbon; also the method of maintaining the bath at proper temperature by circulating it through a 35 heater, and, incidentally, purifying it by filtration in the course of its circulation.

To assist in a full understanding of the invention, an apparatus which is preferably used in practicing the same is shown schematically on the accompanying drawing. In said drawing—

1 represents a separating chamber which is preferably provided with a steam jacket 2 to keep it at a temperature that will avoid 45 condensation of volatiles released therein. Delivering into the upper part of the separating chamber is a spray pipe 3 which leads from any suitable source of aluminum chloride hydrocarbon adapted to supply the 50 material to be separated at a temperature of, say 200° F. Within the chamber 1 is a bath 4 of molten material having the inherent quality of vaporizing at a temperature largely in excess of the vaporizing point 55 of the ingredient or ingredients to be vola-

tilized, as well as the quality of being chemically inert with respect to any of the ingredients thereof, and preferably also of a materially different specific gravity from the ingredient or ingredients of the aluminum chloride hydrocarbon which do not vaporize. Preferably petroleum wax distillate having an initial boiling point approximating 650° F., and permitting the heavy hydrocarbon to settle beneath it, will 60 be used for this bath, but it may be a bath of metal or of salts which would permit the hydrocarbon to remain above it.

In order to keep the bath 4 up to a proper temperature, it may be constantly or periodically withdrawn through pipe 5 by a pump 6 and forced through a filter 7, where any remanent free hydrocarbon will be separated, and on to the heating coil 8 of a furnace 9 whence the material of the bath, at restored 70 temperature, returns through pipe 10 to the separating chamber 1. In the lower portion of separating chamber 1 a heating coil 11 may be arranged for the purpose of maintaining the precipitate from the aluminum 75 chloride hydrocarbon in a sufficiently liquid state to permit of its withdrawal periodically through pipe 12. At top, the separating chamber 1 has an outlet 13 for the ingredients of the aluminum chloride hydrocarbon 80 which are volatile under the temperature of the bath 4, and this pipe leads to an absorption tower 14 of any approved form, but preferably equipped with disks 15 and 16 85 extending alternately from the center and from the side walls and overlapping in a manner to develop a baffled path through which the volatiles flow upwardly and in the course of which they meet a shower of oil that issues from a group of discharge nozzles 17 above the series of baffles and which flows downward over the edges of the baffles in a manner to enter into intimate absorbing relation to the volatiles.

Supply of oil in the tower 14 is maintained through a pipe 18, but the spray 17 is preferably developed from the body of oil 19 in the lower portion of the tower which is constantly being elevated by the Archimedean lift 20 revolved by band pulley 21. Incidentally the revolving body 20 carries the centrally disposed disks 15 and throws the oil therefrom by centrifugal force against the side walls of the tower 14. Fixed and unabsorbed gases in tower 14 may es- 100 105 110

cape through the pipe 25. The product of the tower 14 will be fresh aluminum chloride hydrocarbon with the oil constituent sufficiently thin or light to adapt the product to serve as a catalyst. This product may be drawn off through the bottom pipe 22 as it accumulates in the lower space 23 of the tower, by reason of its specific gravity in excess of that of the body of oil 19. By 10 means of the lift 20, oil 19 may be repeatedly elevated and discharged for contact with the volatiles in the tower until it becomes sufficiently rich in aluminum chloride, when it will automatically settle into the space 23. 15 As fresh aluminum chloride hydrocarbon is drawn off through pipe 22, the supply of oil 19 will be replenished through pipe 18. Heavy hydrocarbon freed from the aluminum chloride and other volatile ingredients 20 by the action of the separating chamber 1, and which will be drawn off through pipe 12, will be in condition to serve commercial purposes, and to it may be added any filtered out hydrocarbon that accumulates in the 25 lower end of the filter 7, whence it is withdrawn through pipe 24.

It is possible to operate a number of recovery chambers in series, the heavy hydrocarbon from one chamber, from which the 30 aluminum chloride has been partially removed, being charged into another chamber to recover the residual aluminum chloride.

I claim:

1. The process of separating heavy hydrocarbon from aluminum chloride, which consists in delivering aluminum chloride hydrocarbon to a bath of liquid material which is maintained at a temperature that is below the vaporizing point of the hydrocarbon and 40 above the vaporizing point of aluminum chloride, thereby volatilizing the aluminum chloride, and then removing the latter in the form of vapor.

2. The process of separating heavy hydrocarbon from aluminum chloride, which consists in introducing aluminum chloride hydrocarbon to a bath of liquid material having a specific gravity that is materially different from that of the hydrocarbon, the 45 liquid material being maintained at a temperature below the vaporizing point of the hydrocarbon and above the vaporizing point of the aluminum chloride, thereby volatiliz-

ing the aluminum chloride and stratifying the hydrocarbon and the material of the 55 bath, and then removing the aluminum chloride in the form of vapor and flowing the hydrocarbon from its stratum.

3. The process of separating heavy hydrocarbon from aluminum chloride hydrocarbon, which consists in heating the aluminum chloride hydrocarbon and presenting it while hot to a bath of liquid material having a specific gravity that is sufficiently different from that of the hydrocarbon to be separated to permit said hydrocarbon and the material of the bath to stratify with relation to each other, and which is maintained at a temperature that is below the vaporizing point of the hydrocarbon and above the 65 vaporizing point of the aluminum chloride, and then drawing off the aluminum chloride in the form of vapor and flowing the hydrocarbon from its stratum in the bath.

4. The process of separating heavy hydrocarbon from aluminum chloride hydrocarbon, which consists in presenting the aluminum chloride hydrocarbon to a bath consisting of a high boiling point hydrocarbon which is maintained at a temperature that is below the vaporizing point of the hydrocarbon to be separated and above the vaporizing point of the aluminum chloride, and then withdrawing the latter in the form of 70 vapor and the hydrocarbon in the form of 75 liquid.

5. The process of separating aluminum chloride from a heavy hydrocarbon with which it is combined, which consists in contacting the aluminum chloride hydrocarbon 90 in a finely divided state with a bath consisting of a high boiling point hydrocarbon, which is of a materially different character from the heavy hydrocarbon from which the aluminum chloride is to be separated; the said bath being maintained at a temperature that is below the vaporizing point of said heavy hydrocarbon and above the vaporizing point of the aluminum chloride; and the aluminum chloride being withdrawn in the form of vapor and said heavy hydrocarbon in the form of a liquid.

Signed at Chicago, Illinois, this 19th day of January, 1922.

ERNEST V. OWEN.
